UNITED STATES PATENT OFFICE.

WILLIAM H. BROWN, OF SYRACUSE, NEW YORK, ASSIGNOR TO H. H. FRANKLIN MANUFACTURING COMPANY, OF SYRACUSE, NEW YORK, A CORPORATION OF NEW YORK.

RECORDING MACHINE.

1,088,671.

Specification of Letters Patent. Patented Feb. 24, 1914.

Application filed December 14, 1908. Serial No. 467,472.

To all whom it may concern:

Be it known that I, WILLIAM H. BROWN, of Syracuse, in the county of Onondaga and State of New York, have invented a new and useful Recording-Machine, of which the following is a specification.

My invention relates to recording machines, and has for its object the production of a particularly simple and efficient recording element therefor, and it consists in the combinations and constructions hereinafter set forth and claimed.

In describing this invention, reference is had to the accompanying drawing, in which like characters designate corresponding parts in all the views.

Figures 1 and 2 are elevations, partly in section, of one form of my recording mechanism, movable parts thereof being shown in Fig. 1 as in their normal or starting positions, and in Fig. 2 as in their positions assumed when cooperating with each other. Figs. 3 and 4 are fragmentary views of opposite edge portions of the recording element. Figs. 5, 6 and 7 are views similar to Fig. 1 of modified constructions of this recording mechanism.

The preferable embodiment of a recording mechanism embodying my invention comprises a movable recording element 1, having gear teeth provided with printing characters thereon, means for holding the recording element in its normal or starting position, means for limiting the movement of said element to different positions, a gear 2 for meshing with said gear teeth, and means 3 for supporting a record-receiving element 4 upon which impressions are made by the printing characters.

Preferably, the recording element 1 comprises a wheel loosely mounted on a suitable horizontal support or axle 5 and having a series of peripheral gear teeth extending partly around the same, a number or one set of said teeth 6 being provided with raised printing characters 7, as 0, 1, 2, 3, etc., at their ends, and others of said teeth constituting another set being unprovided with printing characters one of the latter teeth, as 8, being shorter than the teeth 6 and normally arranged at the printing point. Said element 1 is usually provided with an indicating surface 9 located about diametrically opposite to the series of teeth 6, and provided with characters corresponding to the printing

characters 7 at the ends of said teeth, so that when any predetermined printing character, as 5, is at the printing point, the corresponding indicating character, as 5, will be displayed at the opposite surface of the recording element. To facilitate the reading of the indicating characters, a fixed plate 10 is arranged in proximity to the edge of the recording element 1 at the left hand side thereof, and is provided with a slot 11 with which is registered the indicating character corresponding to the character at the printing point.

The portion of the recording element or wheel 1 provided with the gear teeth 6 and 8, is usually weighted, and the element or wheel 1 is normally arranged with the greater part of such weighted portion above and at the right hand of the axis of said wheel, and, consequently, this weighted portion normally tends to move the element 1 in the direction indicated by the arrow 1. As will be apparent to those skilled in the art, the element or wheel 1 may be moved in the reverse direction by hand or by any suitable mechanism, not illustrated.

The means for holding the recording element 1 in its normal position, comprises a stop 12 which may be moved laterally, or otherwise, from its normal position relatively to the recording element 1 to release said element. This stop preferably engages with a peripheral shoulder 13 on the element 1, the outer end of such shoulder being shown as located farther from the axis of the recording element 1 than the outer ends of the teeth 6, in order to avoid engagement of the stop 12 by the teeth 6 on the return movement of the recording element. It will be understood, however, that providing the stop 12 is held in its position assumed in Fig. 2, i. e., out of the path of the shoulder 13, during the return of the recording element, it is not necessary that said shoulder project a greater distance beyond the periphery of the recording element than the teeth 6. Although the stop 12 is particularly applicable for use with the recording element 1, it will be obvious that any other suitable means may be used in lieu thereof.

The means for limiting the movement of the recording element at predetermined points or positions in its path of movement in order to position predetermined characters at the printing point, may consist of an

adjustable shoulder 14 carried by a suitable support 15 and adjustable relatively thereto in a curved line concentric with the recording element 1, said shoulder 14 being preferably movable in a curved guide in the support 15 and normally lying in the path of the shoulder 13 in order that after the shoulder 13 is released from the stop 12, it will coöperate with the shoulder 14, as shown in Fig. 2, and limit the further movement of the recording element.

Adjustment of the stop 14 to any predetermined number of positions may be effected by hand or by means operated or controlled by the keys of a recording machine, but as I do not wish to limit my present invention to any particular mechanism for effecting or controlling the movement of the stop 14, I have deemed it unnecessary to illustrate and describe such mechanism. When adjusted along the support 15 the stop may be held in position by any suitable means, as a screw movable in a slot in the support 15, but I do not limit this invention to any particular means for holding the stop 14 from movement relatively to said support. It will be apparent however, to those skilled in the art that the shoulder 14 is only one exemplification of means for limiting the movement of the recording element, and that any other suitable mechanism may be used for this purpose.

The gear wheel 2 for meshing with the gear teeth of the recording element 1, is normally out of mesh with such teeth, and is movable toward and from said element 1 into and out of mesh with the gear teeth thereof. This wheel 2 is carried by any suitable movable support 16, and when engaged with the teeth of the recording element 1, is revolved or advanced by said element. Preferably, the wheel 2 is one of a train of calculating wheels and, upon making a complete revolution, serves to advance another wheel of such train a single step. It is obvious, however, that the gear 2 may be any toothed element, the extent of movement of which depends upon the movement of the primary actuating element, as the wheel 1.

The means 3 for supporting a record-receiving element 4, may be of any suitable construction, and is here shown as a revolute drum or platen opposed to the gear teeth of the recording element 1, and normally spaced apart therefrom, said drum being carried by a suitable support 17 and movable toward and from the recording element into and out of engagement with the character 7 at the printing point. Providing the member 1 has not been advanced from its normal or starting position at the time the means 3 is moved toward the printing point, no impression will be made upon

the record-receiving element 4, as the short tooth 8 will be opposed to said means 3.

In operation, the stop 14 is adjusted to one of its various positions, and the shoulder 12 is moved to its position illustrated in Fig. 2 for releasing the recording element 1, whereupon said element advances under the influence of its weighted portion until limited by the stop 14. During the advance movement of the recording element 1, the gear 2 and drum 3 remain in their normal positions, as shown in Fig. 1, but preliminary to the retrograde movement of said element 1, the record-receiving element 4 is moved into and out of its position shown in Fig. 2 for effecting the printing thereon by the character at the printing point, and the gear 2 is moved into the position shown in Fig. 2, so that it will be advanced upon the return movement of the recording element 1. After the element 1 has been returned to its normal or starting position, the gear 2 is disengaged therefrom and moved to the position assumed in Fig. 1.

In Fig. 5, the recording element is shown as a sliding rack 18 having a series of gear teeth 19 similar to the teeth 6 and 8 of the recording element 1. This rack 18 is provided with stop-shoulders 20 on its rear face corresponding to the teeth 19, is normally held from downward movement by a pivoted pawl 21, movable by any suitable means, and coacting with the shoulders 20, and when freed from the pawl 21 is limited in its downward movement at predetermined points or positions by an adjustable stop 22 adjustable along a support 23. After the adjustable stop 22 limits the downward movement of the recording element, the pawl 21 returns to its position for holding said element in its adjusted position.

In Fig. 6 the recording element 1 is illustrated as an arc-shaped rack 24 carried by the free end of a rock-arm 25 loosely mounted at its opposite end on a shaft 26. Said rack 24 is held in its various positions by a pivoted pawl 27 and is limited in its movement when free from the pawl 27 by a stop 28 movable along a convex support 29.

Fig. 7 shows a recording member consisting of a wheel 30 movable in one direction about its axis by a spring 31, and having peripheral teeth 32 similar to the teeth 6 and 8 previously described, and a series of stop-shoulders 33 located about diametrically opposite to the teeth 32. A pivoted pawl 34 coacts with the shoulders 33 to hold the wheel 30 in its adjusted position, and a stop 35 adjustable along a curved support 36 coacts with a peripheral arm 37 on the wheel 30 for limiting the movement of said wheel when free from the pawl 34.

What I claim is:

1. A movable recording element for re-

cording machines, said element having a series of gear teeth for engaging a toothed element, the teeth being provided with printing characters at their ends, and said recording element being advanced solely by gravity, substantially as and for the purpose described.

2. A recording element for recording machines, said element oscillating about a substantially horizontal axis, and having a series of peripheral gear teeth for engaging a toothed element, the teeth being provided with printing characters at their ends, and said recording element also having a weighted portion extending above and at one side of its axis, and overbalancing the opposite portion of said element for advancing the recording element by gravity, substantially as and for the purpose described.

3. A recording element for recording machines, said element oscillating about a substantially horizontal axis, and having its upper portion weighted and provided with a series of peripheral gear teeth for engaging a toothed element, the teeth having printing characters at their ends, and the greater part of such weighted portion being above and to one side of the axis of said recording element, substantially as and for the purpose specified.

4. A gear wheel having two sets of peripheral teeth for engaging an intermeshing gear, one set of said teeth being provided with printing characters, and the other set being unprovided with printing characters, substantially as and for the purpose described.

5. In a recording machine, the combination of a movable recording element having

gear teeth, a number of the teeth being provided with printing characters for being successively advanced to printing position, and another of the teeth being unprovided with a printing character, and being at the printing position, and a toothed element for coöperating with said gear teeth, substantially as and for the purpose set forth.

6. A gear wheel having a part of its periphery provided with teeth for engaging an intermeshing gear, a plurality of such teeth carrying printing characters, said wheel having another portion of its periphery provided with a stop projecting therefrom, substantially as and for the purpose described.

7. In combination in a recording machine, a recording element movable about an axis, and having peripheral gear teeth for engaging a toothed element, the teeth extending partly around the recording element, said recording element also having a peripheral shoulder, the outer end thereof being located farther from the axis of the recording element than the ends of the teeth, and means normally coöperating with the outer end of the peripheral shoulder for preventing advancing movement of the recording element, substantially as and for the purpose set forth.

In testimony whereof, I have hereunto signed my name in the presence of two attesting witnesses, at Syracuse, in the county of Onondaga, in the State of New York, this 12th day of December, 1908.

WILLIAM H. BROWN.
